(57) **CLAIM**

The ornamental design for a mounting bracket, as shown and described.

DESCRIPTION

FIG. 1 is a top and front perspective view of a mounting bracket, showing our new design;

FIG. 2 is a top and rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

FIG. 9 is a top and front perspective view showing one example of use of the mounting bracket of FIG. 1, where the mounting bracket is rotated as compared to FIG. 1 and coupled to an unclaimed display fixture and holding an unclaimed sign; and,

FIG. 10 is a top and front perspective view showing one example of use of the mounting bracket of FIG. 1, where the mounting bracket is coupled to an unclaimed display fixture and holding an unclaimed sign.

The broken lines in the drawings depict portions of the mounting bracket that form no part of the claimed design. The additional broken lines in FIGS. 9 and 10 depict environmental subject matter that forms no part of the claimed design.
